UNITED STATES PATENT OFFICE.

HENRY A. BROWNELL, OF FLINT, MICHIGAN.

CULVERT.

No. 914,110.

Specification of Letters Patent. Patented March 2, 1909.

Application filed August 29, 1908. Serial No. 450,883.

To all whom it may concern:

Be it known that I, HENRY A. BROWNELL, a citizen of the United States, residing at Flint, county of Genesee, State of Michigan, have invented a certain new and useful Improvement in Culverts, and declare the following to be a full, clear, and exact description of the same, such as will enable others skilled in the art to which it pertains to make and use the same, reference being had to the accompanying drawings, which form a part of this specification.

This invention relates to culverts; it has for its object an improved construction of culvert adapted to withstand frost, to be easily laid and to be secure in place.

In the drawings:—Figure 1, is a side elevation of a run of interlocking culvert sections. Fig. 2, is a cross section.

The culvert run is made with three members, of which the lower member 1 extends around the lower arc of the assembled run for approximately one-third of a circle. Along each edge of the member 1 is a rabbet 6; the top of the rabbet 6 is continuous from end to end of the member. The inner tube of the floor of the rabbet also is continuous from end to end of the member. There are slots 8 leading down and inclined outward under the lap and along the corner between the floor and the lap of each rabbet. At one end this member is finished to engage within a collar of an adjacent member; this end of the member is provided with a pin 14; at the other end this member is provided with a collar 10 within which the end of an adjacent member corresponding to the end 11 can engage. The collar is provided with a pin hole 15; preferably the member is braced by ribs 13. The upper members 2 and 3 are similar in construction, except that one is a right hand member, and the other is a left hand member. The terminal collar portion of the upper member 3 is seen at 21 in Fig. 1. The member 2 arches for approximately one-third of a circle; along its lower edge it is provided with a straight seating plane

adapted to engage along the rabbet floor 4, and with projections 7 adapted to engage through the slots 8. The meeting upper edges of the members 2 and 3 are provided with alternating overlaps or projections 19 and 20, the terminal edge of each of which engages over the adjacent portion of the opposite upper member. Each projection 7 terminates with a bead 17; the bead prevents the member 2 from lifting directly.

What I claim is:—

1. In a culvert, in combination with a lower member provided with rabbeted upper edges and with slots through the outer walls along the rabbet, interlocking upper members provided with projections along their lower edge, adapted to engage through said slots, substantially as described. 65
2. In a culvert, in combination with a base member provided with rabbeted edge portions and with suitably spaced slots extending through the same immediately below said rabbeted portions, a detachable upper member rising from each edge portion and meeting thereabove, the meeting edges of each being provided with projections adapted to interlock with the adjacent portion of the other section, and the lower edges of each 75 being provided with depending projections spaced from one another so as to register with the slotted portions in the base member, adapted by engagement therethrough to hold the same from unintended displacement with respect to the base member, substantially as described. 80

3. In a culvert, a member provided at one end thereof with a collar section and with a pin hole through said collar section, and at 85 the other end with a pin adapted to engage through the pin hole of an adjacent section, substantially as described.

In testimony whereof, I sign this specification in the presence of two witnesses.

HENRY A. BROWNELL.
